UNITED STATES PATENT OFFICE.

ALBERTIS E. WRIGHT, OF CHICAGO, ILLINOIS, ASSIGNOR TO A. E. WRIGHT COMPANY, OF CHICAGO, ILLINOIS, A CORPORATION OF ILLINOIS.

DESIGN FOR A BOTTLE.

Application filed May 20, 1925. Serial No. 13,511. Term of patent 7 years.

To all whom it may concern:

Be it known that I, ALBERTIS E. WRIGHT, a citizen of the United States, residing at 1253 Diversy Boulevard, Chicago, in the county of Cook and State of Illinois, have invented a new, original, and ornamental Design for Bottles, of which the following is a specification, reference being had to the accompanying drawing, forming part thereof.

The figure is an elevation of a bottle, embodying the invention.

I claim:

The ornamental design for a bottle as shown.

ALBERTIS E. WRIGHT.
